(57) **CLAIM**

The ornamental design for a tool handle, as shown and described.

DESCRIPTION

FIG. 1 is a perspective view of an embodiment of the tool handle;

FIG. 2 is a top view of the embodiment of FIG. 1, the opposite side being a substantial mirror image;

FIG. 3 is a side view of the embodiment of FIG. 1, the opposite side being a substantial mirror image;

FIG. 4 is a front view of the embodiment of FIG. 1;

FIG. 5 is a rear view of the embodiment of FIG. 1;

FIG. 6 is a perspective view of an alternate embodiment of the tool handle;

FIG. 7 is a top view of the embodiment of FIG. 6, the opposite side being a substantial mirror image;

FIG. 8 is a side view of the embodiment of FIG. 6, the opposite side being a substantial mirror image;

FIG. 9 is a front view of the embodiment of FIG. 6; and, FIG. 10 is a rear view of the embodiment of FIG. 6.

The dotted lines indicate components for illustrative purposes only and form no part of the subject design.
